UNITED STATES PATENT OFFICE.

EDWARD A. MELLINGER, OF CHICAGO, ILLINOIS, ASSIGNOR, BY MESNE ASSIGNMENTS,
TO AUTOMATIC ELECTRIC COMPANY, A CORPORATION OF ILLINOIS.

TELEPHONE APPARATUS AND SYSTEM.

1,330,046.

Specification of Letters Patent.

Patented Feb. 3, 1920.

Application filed March 26, 1907, Serial No. 364,698. Renewed June 5, 1919. Serial No. 301,997.

To all whom it may concern:

Be it known that I, EDWARD A. MELLINGER, a citizen of the United States of America, and resident of Chicago, Cook county, Illinois, have invented a certain new and useful Improvement in Telephone Apparatus and Systems, of which the following is a specification.

My invention relates to telephone systems in general, but more particularly to automatic or semi-automatic telephone exchange systems, and especially to systems in which electrically-propelled and step-by-step-actuated switching machines are employed for extending connection in the direction of the called subscriber. In systems of this kind the calling subscriber controls the exchange apparatus by transmitting electrical impulses over his line, and the distance between the subscriber's station and one or more of the automatic switches is often such that it becomes difficult to effectively transmit impulses over the entire length of the circuit. For this reason repeaters are sometimes employed for relaying the electrical impulses from one section of the circuit to another, so that the impulses which are received by one or more of the switches are not transmitted over the entire length of the circuit, but are simply transmitted over a section of the circuit by one or more relays in a repeater. Repeater for this purpose are employed, for example, in district telephone systems—that is to say, systems in which a main or central exchange is connected with a plurality of sub-central or outlying stations, which latter are in turn directly connected with the subscribers' stations. In a district system of this kind it has been customary to locate the subscribers' line or individual switches and the connector switches at the sub-central or outlying stations, and to locate the selectors at the exchange or main station. Also, in such systems it has been the practice to provide the connectors at the sub-central stations with ringer relays for bridging a source of ringing current across the called subscribers' lines, thus necessitating special connections from the main or central station to the sub-central stations for supplying ringing current to the called subscribers' lines. Furthermore, in systems of this kind selectors have been used for selecting idle trunks containing repeaters, or containing repeater re-

lays, and this, of course, tended toward an increase of apparatus. Again, it was very often desirable to supply the subscribers with talking current derived from a common battery at the main or central station, and this further added to the expense and complication by necessitating connections for feeding talking current through the connectors at the sub-central stations, said connectors being automatic switches by which the final connections are completed directly with the called subscribers' lines. In my improved system, however, I concentrate as much of the apparatus as is possible at the main or central station—that is to say, I provide an arrangement which tends toward a greater concentration of the apparatus at the main or central station than heretofore. For example, I provide selectors which combine the functions of trunk selectors and repeaters and connectors, inasmuch as each of these novel selectors is provided with relays which can be employed for controlling the selector to seize an idle trunk line, which can then be employed for relaying or repeating electrical impulses to the next switch, and which can afterward be used for bridging a source of ringing current across the circuit to supply ringing current to the called subscriber's station. In this way the same relays are not only used for extending a trunk connection from the calling subscriber's line in the direction of the called subscriber, but are also then used for repeating switch-operating impulses to the next switch, so that the selector thus constructed combines the functions of a trunking switch with those of a repeater. Furthermore, the selector thus equipped makes it unnecessary to provide the connectors at the sub-central stations with ringer relays, or with any other apparatus for ringing or signaling purposes, as the selector has an arrangement for bridging a source of ringing current across the circuit after the connector has seized the called subscriber's telephone line. In addition, I provide the said trunk selector with means for bridging a source of talking current across the circuit, after the latter has been completed by the seizure of the called subscriber's line by the connector, and by the taking down of the receiver at the called subscriber's station. With this arrangement the apparatus at the sub-central stations can be of an exceedingly small size.

simple character, the greater part of the apparatus being concentrated at the main or central station, in the manner explained. My improved selectors have various functions when used for extending connections. For example, a calling subscriber first uses one of said selectors as a means for seizing an idle trunk line, then employs the relays of the selector for transmitting or repeating electrical impulses to the next switch, then uses one or more of the relays in the selector for bridging a source of ringing current across the circuit, and finally the called subscriber uses the said selector—that is to say, certain relays thereof—for bridging a source of talking current across the said circuit. In this way the apparatus at the sub-central or outlying stations is employed for performing only connecting and releasing operations, as will hereinafter more fully appear.

In the accompanying drawings, Figure 1 shows diagrammatically a section of the main exchange comprising my combination switch A, a subscriber's line switch B, a subscriber's station C, and a master switch D for controlling the selective operations of the line switch B and of all other line switches in the same group.

Fig. 2 is a similar view showing a sub-central station comprising a modified connector switch E, a called subscriber's station C', and a line switch X for the called telephone line.

Figs. 1 and 2 taken together represent the circuits of an established connection between the substation C and the substation C', in which my combination switch A and the modified connector E are involved.

As thus illustrated the main exchange is provided with the battery B' having its positive terminal preferably grounded at G'; and the sub-exchange is shown provided with a battery B² having its positive terminal preferably grounded at G².

Fig. 3 shows more clearly, in a diagrammatic manner, the line switch B and the master switch D and the connections between them.

Fig. 3^a is a view of the master switch bank K.

Fig. 4 is a diagrammatic perspective view of my improved combination switch A, showing the mechanism and circuits pertaining thereto.

Fig. 5 is a similar view of the modified switch E.

In detail the switches and devices included in the system comprise the following elements.

The substation shown in Fig. 1, which may be of any suitable or approved type, comprises a receiver 2 and a switch-hook 3, which latter has radiating from its body a number of cam-arms 4, 5 and 6, said hook being

pivotedly secured to the keyboard frame (not shown) by a screw 7. In its up and down movements the switch-hook controls certain hereinafter described circuit connections. Furthermore, said substation has a transmitter 8, a ringer 9, an induction-coil 10 having a primary winding 11 and a secondary winding 12, a condenser 13, and impulse wheel 14 which has the usual vertical impulse teeth 15 for operating the vertical impulse spring 16. In addition, the impulse wheel carries a rotary impulse tooth 17 which operates the rotary impulse spring 18. The cam-arm 4 controls the so-called locking arm 19 in such a manner that when the switch-hook rises and before the dial is rotated the insulating tip 20 (upon the end of the locking cam-arm 19, that normally rests in the position shown at substation C') is driven to the inner edge of the angled section of the ground spring 21, whereby when the dial is rotated by the calling subscriber the pin 22 upon the end of the locking dog 23 is able to pass beneath the locking cam to raise the said cam a trifle, causing the said insulating tip 20 to fall behind the said angled section of the ground spring 21, and permitting the said spring to make contact with a co-operating ground spring 24. The engagement of the ground springs 21 and 24 places the ground post 25 in connection with the substation ground G³, whereby, when the subscriber releases the dial, the vertical impulse teeth 15 (by causing the vertical impulse spring 16 to come in contact with the same ground post 25) sends ground impulses over the subscriber's vertical line conductor to the central office; and immediately following, the rotary impulse tooth 17 (by causing the rotary impulse spring 18 to come in contact with the same ground post 25) sends a ground impulse over the rotary conductor. When the switch-hook is down the cam-arm 6 maintains the switch springs 26 and 27 in contact, thereby bridging the ringer 9 in series with the condenser 13 across the line. The springs 28 and 29 are then disengaged, and the primary winding 11 in series with the transmitter 8 is removed from across the line. Even after the switch-hook is raised, and since the finger 30 of the cam-dog 23 controls the engagement of the said springs 28 and 29, and since the said cam-dog rotates in unison with the dial, if the dial is rotated the springs 28 and 29, and, therefore, the subscriber's line conductors are kept separated during said rotation. The signaling device whereby a subscriber may signal another after a connection has been established comprises a push-button 31 and spring 32, which latter normally engages the contact point 33; but when the push-button 31 is pressed the spring 32 leaves the contact point 33 and engages the contact point 34.

which is connected to the substation ground G³. The means whereby the subscriber may release the central station apparatus brought into service comprises three springs 35, 36 and 37 (commonly known as release springs) so controlled by the cam-arm 5 that when the switch-hook descends the release springs are brought into contact, thereby grounding both sides of the subscriber's line simultaneously. The said cam-arm 5 is provided with a lateral flange 38 that is adapted to engage a corresponding lateral flange 39 upon the release spring 37; and as the switch-hook descends, the said flanges 38 and 39 so force the said spring 37 as to crowd the three release springs into electrical contact. When the switch-hook rises, however, the flange 38 engages the flange 39 on the opposite side, so that the spring 37 is not pressed onto the spring 36 at the upward motion of the switch-hook. A somewhat similar provision is made for the vertical and rotary impulse springs 16 and 18; the former is provided with a flange 40^a which is engaged by the vertical impulse teeth 15, and the latter (namely, the rotary impulse spring 18) is provided with a corresponding flange 40 which is engaged by the rotary impulse tooth 17. Furthermore, the switch-hook 3 is provided with a fourth cam member 38^a which, as the switch-hook rises, momentarily engages the spring 39^a, whereby a preliminary ground impulse is transmitted to the rotary line conductor for operating the line switch B. It will be noticed that the part of the switch-hook bearing the cam member 38^a is separated from the part bearing the cam-arms 4, 5 and 6 by the insulating piece 37^a.

40 The line switch B may be of any suitable or approved type. Said line switch is built upon a suitable frame and comprises a plunger 41 and a plunger arm 42. It is also equipped with a cut-off relay 43 and trip magnet 44 and the switch release magnet 45. The said magnets may be secured to the switch frame by any means known to the art. The said release magnet 45 is provided with an armature 46 that is pivoted to a pin 47, the latter rising from the frame of the switch. This armature is normally held away from the pole-pieces of the magnet by a suitable spring 48. The said armature 46 carries pivotally secured to its end 55 a second armature 49 that is controlled by the trip magnet 44 and which is normally held away from the pole-pieces of the said trip magnet by a suitable spring 50. The pin 51 about which the armature 49 oscillates is, of course, carried on a bifurcated terminal of the armature 46. The plunger 41 is pivotally secured by a pin 52 to the plunger arm 42, which latter is in turn pivotally held in place by a pin 53. The 60 said line switch is provided with a bank of

terminals, usually ten in number but only one of which is shown at J. As shown in Fig. 3, and for convenience of illustration, the said terminal J is turned or twisted from its true position with respect to the swing of the plunger 41. The terminal J comprises the springs 54 and 55, 56 and 57, 58 and 59, and 60 and 61. The said springs are normally disconnected from each other, but may be driven into contact when the 70 plunger 41 operates, in the following order: 54 and 55, 56 and 57, 58 and 59, and 60 and 61. Normally the plunger 41 is, however, retained out of engagement with the line switch bank and in engagement with the 75 plunger-controlling shaft 62, which latter is operated by the master switch D. The said plunger is thus held by the armature 49 of the trip magnet 44, which latter is provided with a terminal 63 adapted to engage the rear terminal 64 of the plunger arm 42. The cut-off relay 43 is provided with springs 66, 67 and 67^a for controlling the energizing circuit of the trip magnet 44. The operation of the line switch B in general is as follows: When the subscriber removes his receiver 2 from the switch-hook 3, the latter upon rising sends a preliminary impulse to the central office and energizes the trip magnet 44 for the moment, whereby the armature 49 is attracted and the catch 63 is disengaged from the plunger arm 42. Then a spring 65 rotates the said arm 42 about the pin 53, and if the position of the plunger shaft 62 is such that 80 the plunger 51 is opposite the terminal J, the said plunger 41 is then thrust between the terminal springs 60 and 54, whereby the 85 said terminal springs are closed into contact with their mate springs, as already described. The plunger shaft 62 is provided with a longitudinal channel 78 in which the upper ends of the plungers normally rest. When a plunger is brought to rest it is restored by the momentary energization of 90 the release magnet 45, which release occurs when the subscriber hangs up his receiver and grounds both of his line conductors simultaneously. When thus energized the 95 release magnet attracts the release armature 46, whereby the armature 49 of the trip magnet 44 is raised sufficiently to permit the catch terminal 63 to drop into normal engagement with the plunger arm 42. Then when the release magnet deenergizes the 100 plunger 41 is drawn from the bank and carried into engagement with the shaft 62. It 105 will be understood that the plunger shaft has an oscillatory motion, and at no time does the channel 78 pass out of the range 110 of the rear or upper end 78^a of the plunger 41. The master switch D is provided for operating the plunger shaft 62 and for controlling certain circuits which will be disclosed. 115 120 125 130

It is a comparatively simple switch, having the following details: a motor magnet 69 for operating the ratchet wheel 70, which latter in turn controls the plunger shaft 62. The switch also has a differential relay 71 and an auxiliary relay 72, the former controlling the energizing circuit of the motor magnet 69, and the latter the energizing circuit of all trip magnets 44 of the line switches controlled by said master switch. The said master switch also has a bank K comprising a plurality of individual contact segments α , and a metallic segment 73 common to the said segments α , as shown in Fig. 3. The wiper 74 is adapted to remain in constant engagement with the bank K to maintain at all times some one of the segments α in electrical connection with the common segment 73, except when the wiper 74 passes from the extreme left contact to the extreme right contact, as will be more fully explained. The wiper 74 is operated in a step by step manner by the ratchet wheel 70, through the medium of a cam member 75 rigidly secured to the said wiper 74 and adapted to successively engage the pins 76, 77, 78^a and 79 upon the said ratchet wheel 70. The motor magnet 69 is provided with an armature 77^a upon the end of which there is suitably secured a pawl 80. Each time that the said magnet is energized the pawl 80 engages the ratchet wheel 70, advancing the latter one step. It will be seen, therefore, that as the ratchet wheel 70 advances in a forward direction the wiper 74 advances step by step from right to left, and that when the pin 76, for example, clears the cam 75 the retracting spring 81 restores the wiper 74 to its first position at the right of the bank K and in engagement with the first segment 82. The master switch bank K shown in Fig. 3^a comprises the individual contact segments α separated from the common segment 73 by the insulating strip 73^a. The insulating member 74^a is provided so that when the wiper 74 passes from the extreme left contact 84^a to the extreme right contact 82, the upper part of the wiper 74 slides on the piece 74^a, thus preventing the wiper arm 74 from placing the contact segments α in connection with the common segment 73, whereby some interference might be experienced by the master switch. The said motor magnet 69 is provided with an interrupter comprising a couple of interrupter springs 83 and 84 that are included in the energizing circuit of the said motor magnet, which energizing circuit also comprises the springs 85 and 86 controlled by the differential relay 71. Said interrupter may be of the general type disclosed in United States Patent No. 831,875, granted September 25, 1906, to A. E. Keith, for improvement in interrupter for automatic telephone or other switches. Therefore, when-

ever the differential relay 71 is energized the springs 85 and 86 are pressed into contact, and the motor magnet 69 operates step by step as long as the differential relay 70 remains energized. It is assumed that the terminal J of the line switch B is the first terminal of the line switch bank. The plunger 41 is retained in front of said terminal by the plunger shaft 62 whenever the master switch wiper 74 is in engagement with the bank segment 82; but as the motor magnet 69 advances the wiper 74 onto the second segment 87, all idle plungers are carried opposite the next terminal of the line switch bank. It should be noted that in each line switch bank all of the springs 60 are permanently connected and may be made of one common piece. The springs 59, however, are individual—that is, there is one separate and distinct spring for every bank terminal J, 85 there being, therefore, ten in all in the bank. The springs 58, 54 and 56, like the springs 60, are also common, and the springs 55 and 57, like the springs 59, are individual. For every bank terminal J there is a trunk line 90 of three conductors 88, 89 and 90 leading to a selector, and there is also a normal trunk line comprising the conductors 91, 92 and 93 leading to the connector banks. The subscriber's line conductors 94 and 95 terminate 95 in the springs 54 and 56 which, as has been stated, are common springs. When the subscriber operates the line switch B in connection with the terminal J the subscriber's line conductors 94 and 95 are extended to the 100 vertical and rotary trunk conductors 88 and 89, and thence to the switch A.

The selector switch A is an improvement on the selector switch disclosed in United States Patent No. 815,321, granted March 13, 1906, to Keith, Erickson and Erickson, for improvement in automatic telephone selector switch. It comprises a switch shaft 68 to which are attached the vertical and rotary line wipers 96 and 97 and the private wiper 98. The said shaft is controlled by the calling subscriber through the medium of the vertical and rotary line relays 99 and 100. The former is adapted to operate the vertical magnet 101, which magnet 115 is designed to impart to the switch shaft 68 its vertical movement. The private magnet 102 is controlled by the rotary line relay 100, said private magnet having control of the well-known side switch F that comprises 120 the side switch wipers 103, 104, 105, 106 and 107. When the said private magnet 102 is operated once, the side switch passes to second position, and an energizing circuit is established through the rotary magnet 108, 125 whereby the said magnet becomes operative to rotate the switch shaft 68 in the well-known manner. The vertical and rotary line relays 99 and 100 are adapted to control the release magnet 109 when the sub- 130

scriber desires to release the switch. In addition, said selector switch A is provided with one of the features that are disclosed in the connector switch of United States Patent No. 815,176, granted March 13, 1906, to Keith, Erickson and Erickson, for improvement in automatic telephone connector switch, namely a ringer relay 110. The said relay is adapted when energized, or after a connection has been established with the desired subscriber's line, to disconnect the calling subscriber's line from the called subscriber's line, and to bridge across the latter a ringer generator 111. The said relay 110 performs the said functions through the medium of the ringer relay springs 112, 113, 114, 115 and 116 allotted to said relay. Said switch is, furthermore, provided with a differential relay 117 having two windings 118 and 119. Said differential relay has various functions, among which are the following: The winding 119 being in series with the vertical line relay 99, and the winding 118 being in series with the rotary line relay 100, the said differential relay is adapted to be energized whenever either of said line relays 99 or 100 is energized. However, when the said line relays are energized simultaneously, in a series circuit, the differential relay 117 does not energize; but when the said relays are energized in a multiple circuit the differential relay does energize. The said differential relay is adapted to control the energizing circuit of the ringer relay 110, whereby the called subscriber may be signaled after the desired connection has been established. The said differential relay, furthermore, controls the energizing circuit of the release magnet 109, as will be more fully disclosed. The main talking circuit that passes through the switch A when two subscribers are connected is divided into two sections by the condensers 120 and 121. On the side of the calling subscriber the line relays 99 and 100 and the differential relay 117 are bridged across the said talking circuit; and on the side of the called subscriber there is bridged a double-wound relay 122 through which the charging or talking current is provided for the transmitter of the called subscriber when the said subscriber answers, and, of course, after the side switch wiper 105 has passed into third position and into engagement with the ground terminal. When the called subscriber answers, the said relay 122 then energizes and provides the calling subscriber, in turn, with energizing current for his transmitter. For releasing, the switch has a release relay 122^a which controls the release of the line switch B, as will be described. The switch A is in addition provided with a line switching relay 123 and an auxiliary relay 124, the functions of which will be fully described. The said switch A is, of course, provided with

line and private banks 125 and 126, respectively, which are allotted to the respective line and private wipers 96 and 97, and 98. For purposes to be disclosed, each trunk line leading from the line bank 125 is provided 70 with a private trunk relay a' which controls the auxiliary relay 124.

The connector switch E is an improvement upon the one shown in the aforesaid connector switch patent. As in the said 75 connector switch the switch E comprises the switch shaft 127, the line wipers 128 and 129, the private wiper 130 and the line bank 131, private bank 132, the longitudinal teeth 133 on the shaft 127, circular teeth 134, 80 the vertical magnet 135, the rotary magnet 136, private magnet 137 and the release magnet 138. In addition there is an auxiliary or line relay 139 for controlling the operations of the vertical, rotary and release magnets 135, 136 and 138. The said connector switch is provided with the usual side switch G. The line switch X of the called line (Fig. 2) and the called substation C' being identical with the line 90 switch B and the substation C, further explanation will not be necessary. Like parts being similarly represented in the different figures, there will be no difficulty in understanding the circuits as represented in the 95 following:

The operation of the system will be more fully understood if a description is given of the various steps which occur when one subscriber (C, Fig. 1, for example) calls 100 another subscriber (C', Fig. 2). Assuming that the number of the substation C' is 220, a subscriber at substation C, after removing his receiver and operating the line switch B to connect with the selector A by a preliminary impulse, as already explained, proceeds by operating his dial once for each digit of the desired number. At the first operation of the dial, in accordance with the first digit 2, the vertical trunk conductor 105 88 is grounded twice, and then the rotary trunk conductor 89 is grounded once, whereby the switch A is operated to establish connection with the connector E. The second operation of the dial, in accordance 110 with the second digit 2, causes ground impulses to be likewise sent to the rotary and vertical trunk conductors 181 and 182 for operating the connector switch E, whereby the wipers of the said connector switch are 115 raised to a level with a group of line terminals among which is the terminal of the desired telephone line. When the dial is operated for the last time the shaft of the connector is rotated so that the calling subscriber's line is carried into connection with the called subscriber's line, if the said line 120 is not busy.

The preliminary impulse, to which reference has been made, is sent in when the sub- 130

scriber removes his receiver 2 from the switch-hook and thereby permits the arm 38^a to engage the ground spring 39^a. The rotary line conductor 95 is thus grounded once, and the trip magnet 44 of the line switch B is energized by a flow of current from the substation ground G^a to the ground spring 39^a, thence to the switch-hook and to the conductor 141, and thence to the rotary line conductor 95, conductor 142 at the line switch B, cut-off springs 67, 67^a and 66, trip magnet 44, conductor 143, auxiliary relay springs 144 and 145 to the battery lead 146, and through battery B' to ground G'. As already explained, the trip magnet attracts the armature 49, thus releasing the plunger arm 42 and causing the plunger 41 to be driven into the bank terminal J by the spring 65. The operation of the plunger 41 establishes a number of circuits and produces a number of operations as follows: The bank springs 58 and 59, being pressed into contact, a guarding potential is established at the master switch bank contact 82 for operating the master switch. This guarding potential is established from the said contact point 82 over the conductor 147 to the bank spring 59, thence to the bank spring 58 and through the release magnet 45 to the battery lead 146. The guarding potential thus established at the contact point 82 is negative, and since the master switch wiper is at the time in engagement with the said contact 82 and with the common member 73 of the bank K, an energizing circuit is established through the master switch auxiliary relay 72 and through the winding 148 of the differential relay 71. The current flows from the contact point 82 at the master switch bank K through the wiper 74 to the segment 73, thence over the conductor 149 to the auxiliary relay 72, and through said relay and the winding 148 of the differential relay 71 to the ground terminal G^a. It will be seen that this circuit also includes the release magnet 45 of the line switch B, but the windings of the relays 72 and 71 are of such resistance that sufficient current does not flow to operatively energize the release magnet 45. Both the auxiliary relay 72 and the differential relay 71 energize, and the latter, upon attracting its armature, forces the springs 85 and 86 into engagement, in turn establishing a circuit through the motor magnet 69 from ground G^a through the said springs 85 and 86, and through the motor magnet 69 to the interrupter spring 84, thence to the interrupter spring 83 and to the battery lead 146, and through battery B' to ground G'. The motor magnet 69, upon attracting its armature 77^a, causes the pawl 80 to engage the ratchet wheel 70, rotating the said wheel one step and causing the wiper 74 to leave the contact point 82 and advance onto the contact point 87. Since the plunger shaft 62 is rigid with the wiper 74, the said shaft 62 is also advanced one step, whereby all idle plungers are advanced to a position opposite the next bank terminal of the line switch bank. It will be evident that when the motor magnet 69 attracts its armature the springs 83 and 84 separate, breaking the energizing circuit for the said motor magnet, and when the wiper 74 is advanced onto the bank segment 87 the energizing circuit for the differential relay 71 and for the auxiliary relay 72 is broken, unless this segment is also protected by a guarding potential. In this event the said circuit is not broken and the differential relay 71 will be retained energized, and when the motor magnet armature 77^a reestablishes the energizing circuit for the motor magnet 69 the said magnet is energized once more, and the wiper 74 together with the plunger shaft 62, are advanced one more step. This operation is, of course, repeated as often as the wiper 74 finds protected or guarded contacts. However, as soon as the wiper 74 leaves the last busy contact the deenergization of the differential relay 71 then follows, whereby the differential relay springs 85 and 86 separate before the motor magnet deenergizes and as a result the energizing circuit through the said motor magnet is then permanently broken. It will be noticed that the trip magnet 44 of the line switch is controlled by the auxiliary relay 72, and as a matter of fact all trip magnets of the line switches controlled by the master switch D are thus connected. The object in thus destroying the energizing circuits for the trip magnets of the group is to prevent any subscriber who may remove his receiver at the instant that the master switch D is operating from tripping his individual switch and causing his plunger to seize upon a busy trunk line. The closure of connection between the bank springs 60 and 61, when the plunger 41 is operated, establishes a guarding potential of a positive nature at the private normal conductor 93, from ground G^a, which guarding potential is extended to the connector private bank contacts corresponding to the substation C, whereby no subscriber will be able to interfere with the line after the subscriber has begun to make a call. This guarding potential, furthermore, sends a flow of current through the cut-off magnet 43 of the line switch B from ground G^a through the springs 61 and 60 to the conductor 150, thence through the said cut-off relay 43 to the battery lead 146, then through battery B' to ground G'. The energization of said cut-off relay 43 accomplishes two objects, namely the removal of the short-circuit of the line conductors 94 and 95 through the springs 67 and 67^a from across the subscriber's line, and the disconnection of the trip magnet 44 from the line, so that the

electric impulses that are to follow will not operate to energize the said trip magnet 44. When the plunger 41 presses the springs 54 and 55 into contact, and the springs 56 and 57 into contact, the subscriber's line conductors 94 and 95 are extended to the trunk conductors 88 and 89 and put in connection with the selector A; therefore, after the line switch B is operated as described, the succeeding impulses that come from the substation will be directed to the switch A.

The first digit being 2, when the subscriber operates his dial he grounds the vertical line conductor 94 twice, each time energizing the vertical line relay 99 of the selector A, and at the same time the differential relay 117. The operating current passes from the substation ground G^s through the ground springs 21 and 24 to the ground post 25, thence through the vertical impulse spring 16 to the vertical line conductor 94, line switch bank springs 54 and 55 to the vertical trunk conductor 88 and to the vertical line relay 99, thence through said relay and through the winding 119 of the differential relay 117 to the battery lead 146, thence through battery B' to ground G' . The energization of the differential relay is of no consequence at this time, but the vertical line relay, on pressing the spring 151 onto the ground spring 152, sends a flow of current through the vertical magnet 101 for raising the switch shaft 68. Since the said relay 99 operates twice, the vertical magnet 101 is energized twice, attracting its armature 153, which armature operates to raise the shaft 68 two steps, thus placing the line wipers 96 and 97 and the private wiper 98 opposite the first contact of the second level of the line and private banks 125 and 126. The current that passes through the vertical magnet 101 flows from the ground terminal G^s through the springs 152 and 151, conductor 154, line switching relay springs 196 and 198, conductor 157 to the private springs 158 and 159, conductor 160, side switch wiper 104, contact point 161, conductor 162 to the vertical magnet 101, thence to the battery lead 146, and through battery B' to ground G' . The ground impulse to the rotary line conductor 95 which follows operates the rotary line relay 100 at the selector A, together with the differential relay 117. The operation of the latter relay is still of no consequence. The current flows from the substation ground G^s to the ground post 25, thence to the rotary impulse spring 18, rotary line conductor 95, line switch bank springs 56 and 57 to the rotary trunk conductor 89, thence to the rotary line relay 100 and through the said relay and winding 118 of the differential relay 117 to the conductor 163, back-bridge relay springs 164 and 165 to the battery lead 146, thence through battery B' to ground G' . The

rotary line relay 100, upon energizing, carries the spring 166 into engagement with the ground spring 152, thereby sending an impulse to the private magnet 102 for operating the side switch F. The energizing current passes from ground G^s through the springs 152 and 166, through the line switching relay springs 197 and 199, conductor 169 to the private magnet 102, thence through said magnet to the conductor 170, back-bridge relay springs 164 and 165 to the battery lead 146, thence through battery B' to ground G' . The private magnet 102 energizes and deenergizes, and in so doing permits the side switch arm 171 to pass from first to second position, in the well-known manner. The side switch wiper 103, therefore, passes into engagement with the contact point 172, establishing an energizing circuit for the rotary magnet 108 from ground G^s through the side switch wiper 103 to the contact point 172, rotary magnet 108 and inter-rupter springs 173 to the battery lead 146, thence through battery B' to ground G' . The rotary magnet 108 energizes, therefore, and attracts its armature 174, rotating the shaft 68 so as to carry the line wipers 96 and 97 and the private wiper 98 into engagement with the first contact of the second level of the line and private banks. If the first trunk line leading therefrom is busy, as is well known the private wiper 98 finds a grounded contact which provides potential for reenergizing the private magnet 102, whereby the side switch F is locked in second position; therefore, the side switch wiper 103 is maintained in engagement with the contact point 172 until the wipers are rotated into engagement with some idle trunk line, at which time the energizing circuit through the private magnet 102 is broken and the side switch passes to third position, permanently destroying the energizing circuit for the rotary magnet 108. It will be understood that when the rotary magnet 108 energizes in the first instance, as described, the rotary armature finger 175 engages the private armature 176 and operates the latter so that the private springs 177 and 178 are carried into contact. If the private wiper 98, as has been suggested, finds a grounded contact, a flow of current passes through the said private magnet from the grounded contact to the private wiper 98, thence through the auxiliary relay 124 to the side switch wiper 105, contact point 179, conductor 180, private springs 178 and 177 to the private magnet 102, thence to the conductor 170 and back-bridge relay springs 164 and 165 to the battery lead 146, and through battery B' to ground G' . The private magnet 102, upon energizing, with-holds the armature 176 from the rotary armature finger 175 as the rotary armature 174 recedes, thus locking itself in an ener-

gizing circuit until the said energizing circuit is interrupted, when the private wiper 98 leaves the last grounded contact point. Of course, while the side switch is thus held in second position, and as often as the armature 174 falls back and the interrupter springs 173 are permitted to engage, the said rotary magnet is again energized, and therefore the shaft 68 is rotated step-by-step; but when the private wiper 98 is advanced until the energizing circuit for the private magnet 102 is interrupted, the private armature 176 falls back to the care of the rotary armature finger 175, so that when the armature 174 returns to normal position the side switch F escapes to third position before the rotary magnet 108 has time to again energize. If the first trunk is not busy, however, the rotary armature 174, at the first stroke, operates the private armature 176 through the medium of the rotary armature finger 175, so that the side switch F escapes from second to third position, in the usual and well-known manner. It will be noticed that while the private wiper 98 is traveling over grounded contacts, the energizing circuit for the private magnet 102 passes through the auxiliary relay 124; but the said relay 124 is wound to a very low resistance; while the private magnet 102 is of sufficiently high resistance to cut down the flow of current so that the relay 124 cannot operatively energize. Any suitable resistance may, of course, be given to the coil 124; but it has been found that good results are obtained with a resistance of one-half ohm. Assuming that the wipers are rotated and carried into engagement with the trunk line leading from the tenth terminal of the second level of the banks, then when the side switch F passes to third position the subscriber's line conductors 94 and 95 (which, by the operation of the line switch B, were connected with the trunk conductors 88 and 89) are extended to the trunk conductors 181 and 182 over a circuit which is temporarily opened by the energization of the auxiliary relay 124, which latter energizes as soon as the side switch passes to third position, breaking the connection on one side; and the said relay 124 in turn causes the energization of the line switching relay 123, which latter breaks the connection on the other side. The energizing circuit for the said auxiliary relay 124 extends from the side switch ground G² to the contact point 183, side switch wiper 105, conductor 184, auxiliary relay 124, to the private wiper 98, private trunk relay springs 185 and 186, resistance coil 187 to the battery lead 146; and through battery B' to ground G'. The auxiliary relay 124, upon energizing, shifts the spring 188 away from the spring 189 and into engagement with the spring 190; and the spring 191 into engagement with the

spring 192. When the springs 191 and 192 engage, an energizing circuit is then established through the line switching relay 123 from ground G² through the said springs 191 and 192, conductor 193 to the relay 123, thence through said relay to the battery lead 146, and through battery B' to ground G'. The said relay 123, upon energizing, shifts the spring 194 away from the spring 195, and the springs 196 and 197 away from the springs 198 and 199, respectively, and into engagement with the springs 195 and 200. By studying the combined action of the relays 124 and 123 it will be noticed that the spring 189 of the auxiliary relay 124 constitutes the terminal of the trunk conductor 181; and that the spring 195 of the line switching relay 123 constitutes the terminal of the vertical trunk conductor 182. Furthermore, when the said springs 189 and 195 leave their respective springs 188 and 194, connection is broken between the trunk conductors 181 and 182 and the subscriber's extended line conductors 88 and 89; as already stated. The spring 200 of the line switching relay 123, it will be seen, is also connected permanently with the rotary trunk conductor 181. In addition, the springs 197 and 196 of the line switching relay 123 are directly connected with the springs 151 and 166 of the vertical and rotary line relays 99 and 100; therefore, when the line switching relay 123 and auxiliary relay 124 energize, the trunk conductors 182 and 181 are severed from the trunk conductors 182 and 181, whereby, when the line relays 99 and 100 are operated after the side switch F passes to third position, the impulse will be repeated to the trunk conductors 182 and 181, for operating the connector switch E. Furthermore, when the side switch F passes to third position the seized trunk line is protected by the guarding potential that appears at the private wiper 98, through the auxiliary relay 124, as is usually the case. The private wiper 98 being in engagement with the tenth contact of the second level of the private bank 126, connection is thereby established with the private trunk conductor 181 that extends to the connector E, and through which the releasing of the connector E takes place after the subscribers are through talking.

The second digit being 2, the subscriber again operates his dial to ground the vertical line conductor 94 twice, each time energizing the vertical line relay 99 of the selector A over circuits that are already known. The said relay, upon pressing the springs 151 and 152 into contact, now repeats impulses

to the vertical trunk conductor 182 that leads to the connector E, for energizing the line relay 139 at the said connector. The energizing circuit for the said relay 139 may 5 be traced from ground G⁷ through the springs 152 and 151 to the conductor 154, thence through the line switching relay springs 196 and 195 to the conductor 201, vertical line wiper 96, vertical trunk conductor 182, side switch wiper 202 of the side switch G at the connector E, contact point 203 to the relay 139, thence to battery lead 204, and through battery B² to ground G². Each time that the relay 139 energizes, it 10 presses the springs 205 and 206 into contact, each time energizing the vertical magnet 135, for raising the switch shaft 127 and the line and private wipers 128 and 129 and 130. The circuit through the said vertical 15 magnet 135 begins at ground G¹¹ and extends through the springs 205 and 206, conductor 207, private springs 208 and 209, conductor 210, side switch wiper 211, contact point 212 to the vertical magnet 135, 20 thence to the battery lead 204, and through battery B² to ground G². Each time that the vertical magnet 135 attracts its armature 212 it raises the switch shaft 127 one step, as is well known. The grounding of 25 the rotary line conductor 95, that follows the grounding of the vertical line conductor, energizes the rotary line relay 100, as is already known, over circuits that have been described. Said relay again presses the 30 springs 166 and 152 into contact, thereby grounding the rotary trunk conductor 181, and as a result operating the private magnet 137 of the connector E. The current through the said private magnet flows from 35 ground G⁷ through the springs 152 and 166 to the line switching relay springs 197 and 200, thence to the conductor 213 and to the rotary wiper 97, rotary trunk conductor 181, side switch wiper 214 of the connector E, 40 contact point 215 to the private magnet 137, thence to the battery lead 204, and through battery B² to ground G². As is well known, the private magnet energizes and deenergizes, permitting the side switch G to pass 45 to second position. Therefore, since the side switch wiper 211 shifts into engagement with the contact point 216, when the relay 139 next operates, the rotary magnet 136 responds instead of the vertical magnet 135. 50 The third digit being naught the subscriber operates his dial accordingly, grounding the vertical line conductor 94 ten times, and operating the vertical line relay 99 ten times, and again grounding the vertical 55 trunk conductor 182 each time the said relay 99 is energized. The vertical trunk conductor 182 being grounded ten times, the line relay 139 at the connector E is energized ten times, and the springs 205 and 206 60 are pressed into contact each time. The rotary magnet 136 is thus operated to rotate the shaft 127 ten steps, carrying the line wipers 128 and 129 into engagement with the normal conductors 217 and 218 that lead through the called subscriber's line switch 70 X to the called subscriber's station #220; and the private wiper 130 is carried into engagement with the private normal conductor 219 that terminates in the said line switch X. When the subscriber grounds his 75 rotary line conductor 95 for the last time he operates the rotary line relay 100 at the selector A, which in turn presses the springs 166 and 152 into contact, thus delivering a ground impulse to the rotary line conductor 80 181, as before, and as a result operating the private magnet 137 at the connector E. Thus operating the private magnet 137 after the side switch G is in second position produces one of two results, namely the establishment of final connections with the desired line, or the busy-release of the connector switch E. It will first be considered that the line is not busy and that the private 85 magnet 137, upon operating, sends the side 90 switch G to third position, placing the trunk conductors 182 and 181 in connection with the normal conductors 217 and 218. The normal conductor 217 and the trunk conductor 182 are connected through the side 95 switch wiper 202, contact point 220, conductor 221 and vertical line wiper 128; and the normal conductor 218 and the rotary trunk conductor 181 are connected through the side switch wiper 214, contact point 222, 100 conductor 223 and rotary line wiper 129. It will be noticed that when the side switch wiper 224 of the side switch G at the connector E passes into engagement with the contact point 225 the private trunk relay a' 105 is energized in series with the private magnet 137 of the connector E, through the following circuit: from ground G⁹ at the selector side switch F to contact point 183, side switch wiper 105, conductor 184, auxiliary relay 124, private wiper 98, private trunk relay a', private trunk conductor 181^a, side switch wiper 224 of the connector E, contact point 225, conductor 227 to the private magnet 137, thence to the battery lead 204, and 110 through battery B² to ground G². The private trunk relay a', upon energizing, forces the springs 185 and 186 apart, thus destroying the energizing circuit for the auxiliary relay 124, which relay, upon deenergizing, re- 115 establishes the connection between the rotary trunk conductor 181 and the vertical trunk conductor 88, through the condenser 120. Furthermore, when the auxiliary relay springs 192 and 191 disengage, the line 120 switching relay 123 deenergizes, restoring connection between the vertical trunk conductor 182 and the rotary trunk conductor 89, through the condenser 121 and through the line switching relay springs 194 and 130

195. It will be noticed that the auxiliary relay 124 is still supplied with current that flows through the private trunk relay a' , and through the private magnet 137 of the connector E; but the aggregate resistances of the said coils a' and 137 are sufficiently great to permit the springs which the auxiliary relay 124 controls to be restored, as explained. Not only does the private trunk relay a' energize in the circuit that has been described, but the private magnet 137 also energizes, causing the private magnet springs 228, 209 and 208 to separate, and the springs 208, 229 and 230 to engage. It will be noticed that the private wiper 130 is directly connected with the side switch wiper 269, which side switch wiper, upon passing to third position, engages the grounded contact point 270. Therefore, when connection is made with a desired line a guarding potential from ground G^4 appears at the private wiper 130 and, therefore, at the private normal conductor 219 and at all multiple private bank contacts connected thereto, for protecting the seized line against interference. The guarding potential that appears at the private wiper 130 not only acts as a protecting potential, but also sends a flow of current through the cut-off relay 271 at the line switch X of the called line, for energizing said relay. The object in energizing the relay 271 is two-fold, namely to remove the normal short-circuit established through the cut-off relay springs 274 and 275, and to disconnect the trip magnet 276 from the said springs 274 and 275, for preventing the energization of the trip magnet 276 as soon as the potential for providing the calling subscriber's line with talking battery current appears at the normal conductors 217 and 218. The cut-off relay 271 is designed to act very quickly—in fact, much more quickly than the trip magnet 276, in order to accomplish the purpose stated. The path of the current through said relay 271 may be traced from ground G^4 at the connector side switch G to the contact point 270, thence to the side switch wiper 269, conductor 272, private wiper 130, private normal conductor 219 to the cut-off relay 271, and through said relay to the battery lead 204, thence through battery B^2 to ground G^2 . After connection is established with the desired called subscriber, the calling subscriber at substation C presses his signaling button 31, carrying the spring 32 onto the grounded contact 34, grounding the vertical line conductor 94 from the substation ground G^3 through the ground springs 21 and 24 to the conductor 140, thence to the contact point 34, through the spring 32 and through the springs 29 and 28 to the vertical line conductor 94. Since the line switching relay 123 at the selector A is now deenergized, as explained, grounding the vertical line conductor 94 energizes the vertical line relay 99 and the differential relay 117, with the result that the ringer relay 110 is energized by a flow of current from ground G' through the springs 152 and 151, and through the line switching relay springs 196 and 198 to the private springs 158 and 159, thence over the conductor 160 to the side switch wiper 104, contact point 231, conductor 232, ringer relay 110, conductor 233, through the differential relay springs 234 and 235 (which are now in contact) to the battery lead 146, and through battery B' to ground G' . The ringer relay 110, upon energizing, switches the springs 113 and 115 onto the ringer generator springs 114 and 116, thereby sending a signaling current to the called subscriber's line over the following circuit: from the ringer generator 111 to the springs 114 and 113, thence to the side switch wiper 107, contact point 236, conductor 237, auxiliary relay springs 188 and 189, rotary line wiper 97, rotary trunk conductor 181, connector side switch wiper 214, contact point 222, conductor 223, rotary line wiper 129, rotary normal conductor 218, subscriber's rotary line conductor 238, ringer circuit springs 239 and 240, ringer 241, condenser 242, vertical line conductor 243, vertical normal conductor 217, vertical line wiper 128, conductor 221, contact point 220, side switch wiper 202, vertical trunk conductor 182, vertical line wiper 96, conductor 201, line switching relay springs 195 and 194, conductor 244, contact point 245, side switch wiper 106, ringer relay springs 115 and 116 to the ringer generator 111. The subscriber at substation C, upon hearing the bell ring, removes his receiver 246 from the switch-hook 247, breaking the ringer circuit between the springs 239 and 240, and closing the primary circuit between the springs 248 and 249, when the switch-hook rises, which primary circuit comprises the windings 250 and 251 of the back-bridge coil 122. Over the said primary circuit the transmitter 252 of the called substation is provided with talking battery current, which battery current also energizes the back-bridge relay 122. The current in the said circuit flows from the side switch ground G^9 at the selector A to the side switch wiper 105, thence to the winding 250 of the back-bridge relay 122 to the conductor 253, ringer relay springs 112 and 113, side switch wiper 107, contact point 236, conductor 237, auxiliary relay springs 188 and 189 to the rotary line wiper 97, thence to the rotary trunk conductor 181, connector side switch wiper 214, contact point 222, conductor 223, rotary line wiper 129, rotary normal conductor 218, rotary

line conductor 238, primary winding 254 at the substation C', transmitter 252 through the springs 249 and 248 to the vertical line conductor 243, vertical normal conductor 217, vertical line wiper 128, conductor 221, contact point 220, side switch wiper 202, vertical trunk conductor 182, vertical line wiper 96 at the selector A, conductor 201, line switching relay springs 195 and 194, conductor 244, contact point 245, side switch wiper 106 to the winding 251 of the back-bridge relay 122, thence to the differential relay springs 255 and 235 to the battery lead 146, and through battery B' to ground G'. When the back-bridge relay 122 energizes, the spring 164 is carried onto the spring 256, whereby the calling subscriber is in turn provided with talking battery current for the transmitter 8. The circuit over which this current is supplied extends from ground G^o at the selector A to the side switch wiper 105, thence to the conductor 257, back-bridge relay springs 256 and 164 to the winding 118 of the differential relay 117, rotary relay 100, rotary trunk conductor 89, line switch bank springs 57 and 56 to the rotary line conductor 95, thence through the primary winding 11 and transmitter 8 and through the primary springs 29 and 28 to the vertical line conductor 94, line switch bank springs 54 and 55, vertical trunk conductor 88, vertical line relay 99, winding 119 of the differential relay 117 to the battery lead 146, and through battery B' to ground G'. The subscribers will, of course, be able to communicate with each other over the circuits through which the said talking current flows, which circuits are inductively connected by the condensers 120 and 121, as shown in Figs. 1 and 4. The talking circuits are indicated by the heavily marked lines. Of course, the voice-currents that pass through the primary windings 11 and 254 at the substations are induced in the secondary windings 12 and 258, which windings are in series with the receivers 2 and 246. After the two subscribers are through talking, and if the called subscriber should hang up his receiver first, the energizing circuit that has been described, which comprises the transmitter 252 and the back-bridge relay 122 at the selector A, is broken. The relay 122, of course, deenergizes and the springs 256 and 164, separate, and in turn the talking current for the transmitter 8 of the called subscriber is cut off, and when the spring 165 reengages the spring 164 the rotary line relay 100 and the winding 118 of the differential relay 117 are again connected with the non-grounded terminal of battery B'. The talking current having been cut off, if the calling subscriber then hangs up his receiver he grounds the vertical and rotary line conductors 94 and 95, thus simultaneously energizing the vertical and rotary line relays 99 and 100 of the selector A, and also the differential relay 117. The release of the switches occurs when the current through the said relays 99 and 100 and through the differential relay 117 flows from substation ground G^o through the ground springs 21 and 24 to the release spring 37, thence through the release springs 36 and 35 to the vertical and rotary line conductors 94 and 95, and over circuits that are known through the line relays 99 and 100, and through the windings 119 and 118 of the differential relay 117 to the battery B' and to ground G'. The simultaneous operations of said relays closes a release circuit through the release magnet 109 of the selector A, and through the back-release relay 122^a, when the line relays 99 and 100 press the trunk release springs 259 and 260 together, and the differential relay 117 presses the springs 234 and 235 together. The current in this circuit flows from ground G¹² to the relay 122^a, trunk release springs 259 and 260 to the release magnet 109, thence through the differential relay springs 234 and 235 to the battery lead 146, and through battery B' to ground G'. The release magnet 109, upon energizing, attracts its armature 261, which latter kicks the double dog 262 into normal position, depriving the switch shaft 68 of its support and rotating the side switch F into normal position, in the manner fully described in said connector patent. When the switch shaft and side switch of the selector A are thus restored, the energizing circuit that has been previously described for the private trunk relay a' and the private magnet 137 of the connector E is broken. Of course, the auxiliary relay 124 does not energize when the springs 185 and 186 of the relay a' reengage, because the side switch wiper 105 of the selector A has been restored to first position, and consequently neither does the line switching relay 123 energize; but as soon as the private magnet 137 of the connector E deenergizes, the springs 228 and 209 come into contact, permitting a flow of current to pass through the release magnet 138 from the side switch ground G¹³ to the contact point 263, side switch wiper 264, conductor 265, private springs 228 and 209, conductor 210, side switch wiper 211, contact point 266 to the release magnet 138, thence through said magnet to the battery lead 204, and through battery B² to ground G². The release magnet 138 then attracts its armature 267, which strikes the double dog 268, rotating the latter and depriving the switch shaft 127 of its support and restoring the side switch G to normal position. When

the switch shaft 127 is restored, the line wipers 128 and 129 break connection with the subscriber's normal conductors 217 and 218, and the private wiper 130 disengages 5 from the private normal conductor 219. When the connector switch shaft 127 is released, as already explained, and when the private wiper 130 leaves the private normal conductor 219, the energizing circuit for the 10 cut-off relay 271 of the line switch X is broken, restoring the said switch to the control of the substation #220. At the same time that the release magnet 109 of the selector A energizes, the release relay 122^a 15 also energizes, being in the same circuit; and as a result the springs 277 and 278 are pressed into engagement, with the further result that the release magnet 45 of the line switch B is energized by a flow of current 20 from ground G¹⁵ at the selector A through the said springs 278 and 277 to the trunk conductor 90, thence through the bank springs 59 and 58 of the switch B (Fig. 3) to the release magnet 45, and through the 25 said magnet to the battery lead 146, thence through battery B' to ground G'. Said release magnet 45, upon energizing, attracts its armature 46, and as a result the armature 49 of the trip magnet 44 is raised so that 30 the terminal 63 of said armature 49 latches the plunger arm 42, putting the latter in readiness to withdraw the plunger 41 as soon as the release magnet 45 deenergizes, and when the substation release springs 35, 36 and 37 disengage. When the said 35 springs 35, 36 and 37 do separate, the line relays 99 and 100, together with the differential relay 117 of the selector A, de-energize, and, of course, the trunk release 40 springs 259 and 260 and also the differential relay springs 234 and 235 separate, destroying the energizing circuit for the release magnet 109 and the release relay 122^a. When the release relay springs 278 and 277 45 separate in turn, the energizing circuit for the release magnet 45 of the line switch B (Fig. 3) is cut off, and the said magnet deenergizes, permitting the retracting spring 48 to withdraw the plunger 41 from the bank terminal J and bring it into engagement with the plunger shaft 62. It will be noticed by glancing at Figs. 1 and 3 that the ground potential that energizes the release magnet 45 of the line switch A 50 neutralizes the non-grounded potential that normally exists at the master switch bank contact 82 while the terminal J is busy, and it might appear that the reversal of said potential would cause some trouble with the 55 propulsion of the master switch D, in the event that the wiper 74 should come to rest on the contact point 82 while the said contact 82 is thus grounded; but to meet such a condition the differential relay 71 is provided with a second winding 278^a which 60 is permanently connected with the non-grounded terminal of battery B'. It will be evident, therefore, that whether negative or positive potentials exist at any of the master switch bank contacts *a*, the differential relay 71 will energize, the current flowing either through the winding 148 or through the winding 278^a, depending upon which potential is found by the wiper 74. It will be understood, of course, that the 65 ground potential at the master switch bank K will ordinarily appear there only during the interval of the release, which is rather short. After the release occurs, as described, the switches are all restored to 70 their normal positions, ready to be used by any other subscriber. If it should happen that the calling subscriber releases before the called subscriber—that is, before the talking battery current is removed from 75 the line—the apparatus operates a trifle differently. For example, if the subscriber at substation C grounds his vertical and rotary line conductors 94 and 95 by hanging up his receiver, the first result of this is 80 that the rotary line relay 100 and the winding 118 of the differential relay 117 are short-circuited or shunted through ground, since the back-bridge relay 122 is energized at the time. The short-circuit extends between the substation ground and the selector side switch ground G'. It was pointed out that when the back-bridge relay 122 energized, the spring 164 engaged the grounded spring 256, which latter is directly connected with ground G^o; therefore, the inside terminal of the rotary trunk conductor 89 is normally grounded during conversation. Consequently, after the subscriber at 85 substation C grounds the rotary line conductor 94, it will be evident that the current through the rotary line relay and winding 118 of the differential relay 117 is cut off. The rotary line relay 100, of course, de-energizes, and the trunk release spring 260 90 for the time being recedes from the spring 259, but the differential relay 117 energizes, for reasons that have already been explained. When the differential relay springs 235 and 236 separate, the back-bridge relay 122 is de-energized and the called subscriber's line is deprived of talking battery current when the springs 164 and 256 separate, while the inside terminal of the rotary side of the line is restored to normal engagement with the 95 non-grounded terminal of battery B' as soon as the spring 164 advances enough to reengage the spring 165. The rotary line relay 100, therefore, reenergizes by a flow of current in the reverse direction, and the differential relay 117 is further strengthened by the reverse flow through the winding 118. The reenergization of the rotary line relay 100 causes the reengagement of the trunk release springs 259 and 260; and since the 100

differential relay 117 has in the meantime advanced the spring 235 into engagement with the spring 234, there occurs the energization of the vertical line relay 99, of the rotary line relay 100, and of the differential relay 117, which, as has been previously pointed out, establishes an energizing release circuit through the release magnet 109 of the selector A and through the release relay 122^a. The succeeding steps in the release are, of course, the same as those which have already been explained. If the called subscriber's line had been busy the connector side switch G would not have passed to third position, as already stated, but to the contrary the said connector would have been released and the side switch would have been thrust into first position. Taking up the call at that stage, when the calling subscriber grounds the rotary line conductor 95 at the end of the last digit naught, as has been pointed out, the rotary line relay 100 of the selector A energizes and sends a ground impulse to the rotary trunk conductor 181 that leads to the connector E. The said impulse is received by the private magnet 137 which, upon energizing, forces the private springs 229 and 230 into contact before the side switch G has had time to trip to third position. The private wiper 130 has, previous to this, been carried into engagement with a grounded contact point; consequently, since the side switch G is in second position, at the instant that the private springs 229 and 230 engage, a flow of current is sent through the release magnet 138 over the following circuit: from the grounded contact point to the private wiper 130, thence to the side switch wiper 269, contact point 279, conductor 280, private springs 229 and 230, conductor 281 to the release magnet 138, thence to the battery lead 204, and through battery B² to ground G². The release magnet 138, of course, attracts its armature 267, restoring the side switch G and switch shaft 127. The subscriber at substation C, thinking that the connection has been established, presses the signaling button 31, whereby the vertical line conductor 94 is grounded. The effect of grounding the vertical line conductor at this time is to energize the vertical line relay 139 at the connector E, thereby stepping up the shaft 127, as explained. The subscriber at substation C then receives a busy-signal from the busy-signaling machine L (Fig. 1) that comprises the induction-coil 282 which is provided with a primary winding 283 and a secondary winding 284. The current passes from the secondary winding 284, conductor 285, auxiliary relay springs 190 and 188 (bearing in mind that the relay 124 is energized and in an operated position at this particular time, as explained), conductor 287, contact point 236 of the selector A, side switch wiper 107, ringer relay springs 113 and 112, conductor 253, condenser 120, vertical trunk conductor 88, line switch bank springs 55 and 54, vertical line conductor 94, through the primary winding 11 at the substation C to the rotary line conductor 95, thence to the line switch bank springs 56 and 57 to the rotary trunk conductor 89, rotary line relay 100, winding 118 of the differential relay 117, back bridge relay springs 164 and 165 to the battery lead 146 and back to the coil 284. The busy current is induced in the secondary winding 12 of the induction-coil 10 at the substation C, which current then flows through the receiver 2, and which is, of course, heard by the subscriber. He then understands that the line is busy and restores his receiver, grounding the vertical and rotary line conductors 94 and 95 as before, and energizing the vertical and rotary line relays 99 and 100 and the differential relay 117 of the selector A; and the vertical line relay 139 and the private magnet 137 of the connector E are also energized simultaneously when the side switch G is in first or second position, closing an energizing circuit through the connector release magnet 138 extending from ground G¹ through the springs 205 and 206, private magnet 138 to the battery lead 204, thence through battery B² to ground G². The release magnet 138, upon energizing, operates as before to restore the connector switch E. The vertical line relay 99 and the rotary line relay 100 of the selector A energize simultaneously, whereby the release magnet 109 and the release relay 122^a of the said switch A are energized, as previously explained, producing the release of the said switch and of the line switch B. Of course, when the side switch F of the selector A passes to first position the auxiliary relay 124, as well as the line switching relay 123, deenergize; and when the substation release springs 35, 36 and 37 disengage, all of the switching apparatus is fully restored, as explained.

In the selector A the various coils may be wound to any suitable resistance, but it has been found that good results are obtained when the line relays 99 and 100 are of one hundred ohms each; windings 118 and 119 of the differential relay 117 two hundred and fifty ohms each; windings of the back-bridge relay 122 three hundred and fifty ohms each; line switching relay 123 twenty-three hundred ohms; auxiliary relay 124 one-half ohm; ringer relay 110 five hundred ohms; private magnet 102 three hundred and fifty ohms; release relay 122^a one-half ohm; private trunk conductor relay a' sixty ohms; and in the connector E the line relay 139 five hundred ohms, and the private magnet 137 three hundred and fifty ohms. In

the line switch B the resistance of the release magnet 45 may be sixty ohms, the trip magnet 44 sixty ohms, and the cut-off relay 43 may be from one thousand to one thousand and three hundred ohms.

From the foregoing it will be seen that I provide selectors which have four functions—to-wit, the selection of idle trunk lines, the relaying or repeating of switch-operating electrical impulses to other switches, the bridging of a source of ringing current across the trunk lines which have been extended to the called subscribers' lines, and the controlling of the supply of talking current from the common battery to the temporarily established talking circuit between calling and called subscribers. It will be understood, of course, that the connectors E can be less in number than the total number of subscribers' lines, and that the selectors A can be the same in number as the said connectors, whereby the automatic trunking through the exchange is conducted on a percentage basis. The subscribers' line or individual switches B will, of course, be the same in number as the subscribers' telephone lines, and the latter can be divided into groups, in the well-known manner. For a larger exchange the apparatus can be increased in order to provide two or more selectors between the individual switches and the connectors—that is to say, so as to enable each calling subscriber to employ two or more selectors for extending connection to an idle connector. In such case it will also be understood that the calling subscriber will only employ one of the selectors of the type indicated in Fig. 1, as whatever other selectors are necessary in order to extend the connection can be of the regular or ordinary type.

What I claim as my invention is:

1. A telephone system comprising a connector, a selector, a talking circuit including the selector and connector, a plurality of batteries, means in the selector for bridging one battery across the circuit to supply talking current to both ends thereof, circuits for operating the connector from another of said batteries and a line relay for controlling the setting up operation of said selector, said relay included in the path of said current.
2. A telephone system comprising a temporarily established talking circuit between a calling and a called subscriber's line, a selector and a connector in said circuit, said selector provided with means for controlling the operations of the connector, and also with means whereby it may be operated to extend the talking circuit from the calling subscriber to the connector before said connector is operated, and means for supplying talking current through the selector to both ends of the talking circuit.

3. A telephone system comprising a temporarily established talking circuit, means for dividing said circuit into inductively connected sections, automatic switches in said circuit, means for repeating or relaying switch-operating impulses from one section of said circuit to another, and means for supplying talking current through one of said switches, other than the final one, to both ends of said talking circuit, said second means including a relay, said relay included in the path of said current.

4. A telephone system, means for establishing a talking circuit comprising trunk lines, an automatic trunk selector provided with means for relaying or repeating impulses to any selected trunk line, and means for supplying ringing or signaling current through said selector to any selected trunk line, a motor magnet for said selector, said magnet controlled over circuits excluding said talking circuit.

5. A telephone system, means for establishing a talking circuit comprising trunk lines, an automatic trunk selector provided with means for relaying or repeating impulses to any selected trunk line, means for supplying ringing or signaling current through said selector to any selected trunk line, and means for supplying talking current through said selector to any selected trunk line, a motor magnet for said selector, said magnet controlled over circuits excluding said talking circuit.

6. A district telephone system comprising a central station, sub-central stations, subscribers' telephone lines terminating at said sub-central stations, trunk lines between the central station and the sub-central stations, and means at the central station for supplying talking current over the trunk lines to the calling and called telephone lines terminating at the sub-central stations.

7. A telephone system comprising a main central station, sub-central stations, trunk lines between the main central station and the sub-central stations, subscribers' telephone lines terminating at the sub-central stations, a source of ringing current at the central station, and means at the central station for bridging said source of ringing current across any trunk line by which connection has been extended to a called subscriber's telephone line.

8. A telephone system comprising a trunk line, a called telephone line, automatic means for extending connection from the trunk line to the telephone line, a source of ringing current, and means under the control of the calling subscriber after the connection is completed for bridging said source of ringing current across the trunk line, whereby ringing current is sent over the entire trunk line to signal the called subscriber.

9. A telephone system comprising tele-

- phone lines, suitable switches for extending connection to said telephone lines, automatic trunking means for trunking calling telephone lines into connection with idle switches, and means for supplying talking current through said automatic trunking means to the telephone lines, the operation of said automatic trunking means being initiated when the subscriber raises his switchhook.
10. A telephone system comprising telephone lines, suitable switches for extending connection to said telephone lines, automatic trunking means for trunking calling telephone lines into connection with idle switches, and means for supplying ringing current through the said trunking means to the called telephone lines; the operation of said automatic trunking means being initiated when the subscriber raises his switchhook.
11. In a telephone system, the combination of an auxiliary relay, a line switching relay, a rotary line wiper, a vertical trunk conductor, means by which the auxiliary relay controls the energizing circuit of the switching relay, and means by which said auxiliary relay controls the connection between the rotary line wiper and the vertical trunk conductor.
12. In a telephone system, the combination of a line switching relay, a pair of springs, a pair of trunk conductors, means by which said relay is adapted to open one side of the line, means by which the said relay is adapted to switch said springs directly into connection with the said conductors, and a side switch, said relay adapted for repeating or relaying electrical impulses to the trunk line after the side switch passes to third position.
13. In a telephone system, subscribers' lines, a first trunk line common to said lines, a second trunk line having three conductors, means for automatically extending connection to said second trunk line, a relay individual to said first trunk line controlling the continuity of the connection extended to the second trunk line, a relay having its winding included in the third conductor of said second trunk line, and an energizing circuit for said first-mentioned relay, said energizing circuit controlled by the said relay in the third conductor of the second trunk line.
14. A telephone system comprising subscribers' lines, a three-conductor trunk line, automatic means common to said subscribers' lines for extending connection to said trunk line, a relay having its winding included in the third conductor of said trunk line, and a circuit through said automatic means controlled by said relay.
15. A telephone system comprising telephone lines, a connector for automatically seizing and extending connection to any one of said lines, said connector provided with terminals of said lines arranged in a plurality of levels, means for selecting a terminal in any level, a single line relay and a private magnet connected directly to the trunk line, by which operations of the connector are controlled, and a side switch operated by said private magnet.
16. A telephone system comprising subscribers' lines, a plurality of three-conductor trunk lines, automatic means common to said subscribers' lines for extending connection to an idle one of said trunk lines, a relay for the third conductor of each trunk line, and an electromagnet in said automatic means adapted to be controlled by any one of said relays.
17. A telephone system comprising a plurality of three-conductor trunk lines, automatic means for extending connection to an idle one of said trunk lines, a relay for the third conductor of each trunk line, means for energizing said relays, an electromagnet included in said automatic means, and means for energizing said electromagnet by the deenergizing of any one of said relays.
18. A telephone system comprising a three-conductor trunk line, automatic means for extending connection to said trunk line, automatic means for extending connection from the other end of said trunk line, relays in both said automatic means adapted to remain energized during conversation over the trunk line, and an energizing circuit including said relays and third conductor of the trunk line in series.
19. In a telephone system, subscribers' lines, a plurality of trunk lines common to said lines, automatic means for selecting an idle one of said trunk lines, a relay allotted to each trunk line, said relays associated with the trunk line terminals which are adapted to be seized by said automatic means, means for keeping the talking circuit between said line and trunk open, and means controlled by the relay associated with said idle trunk for restoring said talking circuit for talking purposes.
20. In a telephone system, subscribers' lines, a plurality of trunk lines common to said subscribers' lines, automatic means for selecting idle trunk lines, a relay allotted to one end of each trunk line, and switching means at the other end of said trunk lines controlled by said relays, means for keeping the talking circuit between said line and trunk open, and means controlled by the relay associated with said idle trunk for restoring said talking circuit for talking purposes.
21. In a telephone system, a private magnet, a battery, a trunk-line having a trunk conductor excluded from the talking circuit, and a relay adapted to remain energized in series with the private magnet and

- conductor and battery during conversation over the voice conductors of the trunk line.
22. In a telephone system, a calling telephone line, a called telephone line, means including an automatic selector and an automatic connector for extending a talking connection from the calling line to the called line, said connection extended to said connector before the connector is operated, means controlled by mechanism in the selector for supplying talking current to the calling line, and suitably controlled means for supplying talking current to the called line, the operation of the selector for extending the talking circuit being dependent upon the subscriber's telephone switchhook being raised.
23. In a telephone system, a calling telephone line, a called telephone line, means including an automatic selector for extending a trunk connection from the calling line to the called line, a pair of line relays for controlling the operations of said selector, means for supplying talking current, suitable connections for feeding the talking current through the windings of said relays to the calling subscriber's line, and other coils in said selector and connections for feeding the talking current to the called subscriber's line.
24. In a telephone system, a calling telephone line, a called telephone line, means including an automatic trunk selector for extending a trunk connection from the calling line to the called line, a common battery, means in said selector for bridging the common battery across the calling telephone line, and means in said selector for bridging said battery across the trunk connection extending to the called telephone line, whereby talking current is supplied through the selector to both telephone lines, the operation of the selector for extending the talking circuit being dependent upon the subscriber's telephone switchhook being raised.
25. In a telephone system, a calling telephone line, a called telephone line, means including an automatic trunk selector for extending a trunking connection to the called telephone line, a source of talking current, and means in said selector responsive to the called subscriber for feeding talking current to both lines.
26. In a telephone system, a calling telephone line, a called telephone line, means including an automatic trunk selector for extending a trunking connection to the called telephone line, a source of talking current, and a pair of coils in said selector and a battery for feeding talking current to the called line, said battery interposed between said coils.
27. In a telephone system, a trunk-line having three conductors, means for automatically extending connection to said trunk-line, having vertical motion to select groups and rotary motion to connect with a line in the selected group, a relay controlling the continuity of the connection extended to the trunk-line, a relay having its winding included in the third conductor of said trunk-line, and an energizing circuit for said first-mentioned relay, said energizing circuit controlled by the said relay in the third conductor of the trunk-line.
28. A telephone system comprising a three-conductor trunk-line, automatic means for extending connection to said trunk-line, having vertical motion to select groups and rotary motion to connect with a line in the selected group, a relay having its winding included in the third conductor of said trunk-line, and a circuit through said automatic means controlled by said relay.
29. A telephone system comprising telephone lines, a connector for automatically seizing and extending connection to any one of said lines, having vertical motion to select groups and rotary motion to connect with a line in the selected group, said connector provided with terminals of said lines arranged in a plurality of levels, means for selecting a terminal in any level, a single line relay and a private magnet connected directly to the trunk line, by which the operations of the connector are controlled, and a side switch operated by said private magnet.
30. A telephone system comprising a plurality of three-conductor trunk-lines, automatic means for extending connection to an idle one of said trunk-lines, having vertical motion to select groups and rotary motion to connect with a line in the selected group, a relay for the third conductor of each trunk-line, at the end thereof toward the calling subscriber, and an electromagnet in said automatic means adapted to be controlled by any one of said relays.
31. A telephone system comprising a plurality of three-conductor trunk-lines, automatic means for extending connection to an idle one of said trunk-lines, having vertical motion to select groups and rotary motion to connect with a line in the selected group, a relay for the third conductor of each trunk-line, means for energizing said relays, an electromagnet included in said automatic means, and means for energizing said electromagnet by the deenergizing of any one of said relays.
32. A telephone system comprising a three-conductor trunk-line, automatic means for extending connection to said trunk-line, automatic means for extending connection from the other end of said trunk-line, having vertical motion to select groups and rotary motion to connect with a line in the selected group, relays in both said automatic means adapted to remain energized.

- during conversation over the trunk-line, and an energizing circuit including said relays and third conductor of the trunk-line in series.
5. 33. In a telephone system, subscribers' lines, a plurality of trunk-lines common to said lines, automatic means for selecting an idle one of said trunk-lines, having vertical motion to select groups and rotary motion to connect with a line in the selected group, a relay allotted to each trunk-line, said relays associated with the trunk-line terminals which are adapted to be seized by said automatic means, means for keeping 10 the talking circuit between said line and trunk open, and means controlled by the relay associated with said idle trunk for restoring said circuit for talking purposes.
34. In a telephone system, a plurality of 20 trunk-lines, talking conductors comprising said trunk lines, automatic means for selecting idle trunk-lines having vertical motion to select groups and rotary motion to connect with a line in the selected group, a 25 relay allotted to one end of each trunk-line, and switching means at the other ends of said trunk-lines controlled by said relays, said automatic means comprising magnets controlled by said relays over circuits excluding 30 said talking conductors.
35. In a telephone system, a calling telephone line, a called telephone line, means including an automatic selector and an automatic connector for extending trunk connection from the calling line to the called line, having vertical motion to select groups and rotary motion to connect with a line in the selected group, means controlled by 35 mechanism in the selector for supplying talking current to the calling line, and suitably controlled means also in the selector for supplying talking current to the called line.
36. In a telephone system, a calling telephone line, a called telephone line, means including an automatic trunk selector for 45 extending a trunk connection from the calling line to the called line, having vertical motion to select groups and rotary motion to connect with a line in the selected group, a common battery, means in said selector controlled by the called subscriber for bridging the common battery across the calling telephone line, and means in said selector for bridging said battery across the 50 trunk connection extending to the called telephone line, whereby talking current is supplied through the selector to both telephone lines.
37. In a telephone system, a calling telephone line, a called telephone line, means including an automatic trunk selector for 55 extending a trunking connection to the called telephone line, having vertical motion to select groups and rotary motion to connect with a line in the selected group,
- a source of talking current, and means in said selector responsive to the called subscriber for feeding talking current to both lines.
38. In a telephone system, a trunk line, 70 a called subscriber's line, and a selector provided with means for sending ringing current over the trunk-line to the individual line of the called subscriber, and a progressively movable connector switch for connecting the selector with the called line, the operation of said selector being dependent upon the switch hook at the telephone being raised.
39. In a telephone system, a line relay, a 80 plurality of progressively movable switches, local circuits for controlling one of said switches, and trunk circuits for controlling another of said switches, said circuits successively controlled by said relay, means for 85 supplying talking current through the coil of said relay to the calling subscriber, and a coil individual to said one switch through which talking current is supplied to the called subscribers.
40. In a telephone system, a plurality of line relays less in number than the subscribers having access thereto, progressively movable switches, local circuits for controlling one of said switches, and trunk circuits 90 for controlling another of said switches, said circuits successively controlled by said relays, means for supplying talking current through the coils of said relays to calling subscribers, and coils in said one switch 100 through which talking current is supplied to the called subscribers.
41. A telephone system, means for establishing a talking circuit comprising a trunk line, an automatic switch to which the said 105 trunk line leads, a pair of line relays, a progressively movable automatic switch associated with said relays and controlled thereby for extending connection to said trunk line, electromagnet controlled step-by-step mechanism for said switch, and an impulse sender by which a calling subscriber controls the 110 energizing of said electromagnetic means through the medium of said relays via circuits excluding said talking circuit.
42. A telephone system comprising a connector, a selector, a talking circuit including the selector and connector, a plurality of batteries, an electromagnetically controlled auxiliary switch and an electromagnet in the 115 selector for bridging one battery across the circuit to supply talking current to both ends thereof, and circuits for operating the connector from another of said batteries.
43. A telephone system comprising a 120 temporarily established talking circuit between a calling and a called subscriber, a selector and a connector in said circuit, said selector provided with means for controlling the operations of the connector and also with 125
- 130

means whereby it may be operated to extend the talking circuit from the calling subscriber to the connector before the connector is operated, and a battery and circuits comprising resistance coils for supplying talking current through the selector to both ends of the talking circuit.

44. A telephone system comprising a temporarily established talking circuit, a plurality of switches, a pair of line relays to which the said switches are successively responsive, and a battery and circuits comprising resistance coils for supplying talking current through one of said switches, other than the final one, to both ends of the talking circuit.

45. A telephone system comprising a temporarily established talking circuit, condensers dividing said circuit into inductively connected sections, automatic switches in said circuit, a relay controlled over the talking circuit for repeating or relaying switch-operating impulses from one section of said circuit to another, and a battery and circuits comprising resistance coils for supplying talking current through one of said switches, other than the final one, to both ends of said talking circuit.

46. A telephone system comprising trunk lines, an automatic trunk selector provided with a relay for relaying or repeating impulses to any selected trunk line, talking conductors in said trunk selector, said relay connected to said conductors, and a source of signaling current, signaling circuits, a signaling circuit controlling relay for supplying ringing or signaling current through said selector to any selected trunk line, and a motor magnet for said selector, said magnet controlled via circuit excluding said talking conductors.

47. A telephone system comprising trunk lines, an automatic trunk selector provided with a relay for relaying or repeating impulses to any selected trunk line, a source of signaling current, signaling circuits, and a signaling circuit controlling relay for supplying ringing or signaling current through said selector to any selected trunk line, a battery and circuits comprising resistance coils for supplying talking current through said selector to any selected trunk line, and a motor magnet for said selector, said magnet controlled via circuits excluding said talking conductors.

48. In a telephone system, subscribers' lines, a trunk line having three conductors, a progressively movable switch common to said subscribers' lines, means for connecting any one of said subscribers' lines with said switch, and for operating said switch for automatically extending connection to said trunk line, a relay controlling the continuity of the connection extended to the trunk line, a relay having its winding included in

the third conductor of said trunk line, and an energizing circuit for said first-mentioned relay, said energizing circuit controlled by the said relay in the third conductor of the trunk line.

70

49. A telephone system comprising subscribers' lines, a three-conductor trunk line, an automatic progressively movable switch common to said subscribers' lines, means for connecting any one of said subscribers' lines with said switch and for operating said switch for extending connection to said trunk line, a relay having its winding included in the third conductor of said trunk line, and a circuit through said switch controlled by said relay.

75

50. A telephone system comprising subscribers' lines, a plurality of three-conductor trunk lines, a progressively movable switch common to said subscribers' lines, means for connecting any one of said subscribers' lines with said switch and for operating said switch for extending connection to an idle one of said trunk lines, a relay for the third conductor of each trunk line, and an electromagnet in said switch adapted to be controlled by any one of said relays.

80

51. A telephone system comprising a plurality of three-conductor trunk lines, a progressively movable switch for extending connection to an idle one of said trunk lines, a relay for the third conductor of each trunk line, means for energizing said relays, an electromagnet included in said switch, and means for energizing said electromagnet by the deenergizing of any one of said relays.

85

52. A telephone system comprising a three-conductor trunk line, a progressively movable switch for extending connection to said trunk line, a progressively movable switch for extending connection from the other end of said trunk line, a pair of relays individual to said trunk line adapted to remain energized during conversation over the trunk line, and an energizing circuit including said relays and third conductor of the trunk line in series.

90

53. In a telephone system, subscribers' lines, a plurality of trunk lines, a progressively movable switch common to said subscribers' lines, means for connecting any one of said subscribers' lines with said switch and for operating said switch for extending connection to an idle one of said trunk lines, a relay allotted to each trunk line, said relays associated with the trunk line terminals which are adapted to be seized by said switch, and operating magnets in said switch controlled by said relays.

115

54. In a telephone system, a calling telephone line, a called telephone line, an operating battery, an impulse sender at the calling telephone, an automatic selector and an automatic connector for extending trunk connection from the calling line to the called

line, a battery, a pair of resistance coils and circuits in the selector controlled by the response of the called subscriber for supplying talking current to the calling line, and 5 suitably controlled circuits comprising said battery, resistance coils and circuits for supplying talking current to the called line.

55. In a telephone system, a calling telephone line, a called telephone line, a battery, 10 an impulse sender in the calling line, an automatic trunk selector for extending a trunk connection from the calling line to the called line, a common battery, a pair of magnets in said selector for bridging the common 15 battery across the calling telephone line upon the response of the called subscriber, and an auxiliary electromagnetically controlled switch in said selector for bridging said battery across the trunk connection extending to the called telephone line, whereby talking current is supplied through the 20 selector to both telephone lines.

56. In a telephone system, a calling telephone line, a called telephone line, a battery, an impulse sender in the calling line, 25 trunk lines common to said lines, an automatic trunk selector for selecting an idle one of said trunk lines to extend a trunking connection toward the called telephone line, 30 a source of talking current, and an auxiliary electromagnetically controlled switch and a pair of relays in said selector responsive to the called subscriber for feeding talking current to both lines.

57. A telephone system comprising a connector, a selector having vertical motion to select groups and rotary motion to connect with a line in the selected group, a talking circuit including the selector and connector, 40 a plurality of batteries, an auxiliary switch in the selector for bridging one battery across the circuit to supply talking current to both ends thereof, and circuits for operating the connector from another of said batteries.

58. A telephone system comprising a temporarily established talking circuit, a selector and a connector in said circuit having vertical motion to select groups and rotary motion to connect with a line in the selected group, said selector provided with relays for controlling the operations of the connector, and a source of current, said selector having also circuits comprising resistance coils and 50 circuit controlling relays for supplying talking current through the selector to both ends of the talking circuit, said circuits comprising circuit contacts under the control of relays in said selector.

59. A telephone system comprising a temporarily established talking circuit, a plurality of switches having vertical motion to select groups and rotary motion to connect with a line in the selected group, a pair of 65 line relays to which the said switches are

successively responsive, and circuits comprising an impedance for supplying talking current through one of said switches, other than the final one, to both ends of the talking circuit, said circuits controlled by 70 relays in said one switch.

60. A telephone system comprising trunk-lines, an automatic trunk selector provided with relays and auxiliary circuits for relaying or repeating impulses to any selected 75 trunk-line, having vertical motion to select groups and rotary motion to connect with a line in the selected group, and a source of signaling current and signaling circuits associated with said selector and controlled by 80 relays therein for supplying ringing or signaling current through said selector to any selected trunk-line, magnets in said trunk selectors, said magnets controlled by said first relays via circuits independent of said 85 signaling circuit.

61. A telephone system comprising trunk-lines, an automatic trunk selector provided with relays and circuits controlled thereby for relaying or repeating impulses to any 90 selected trunk-line, having vertical motion to select groups and rotary motion to connect with a line in the selected group, a source of signaling current and signaling circuits associated with said selector and 95 controlled by relays therein for supplying ringing or signaling current through said selector to any selected trunk-line, and a battery and circuits associated therewith having impedance for supplying talking 100 current through said selector to any selected trunk-line, magnets in said trunk selectors, said magnets controlled by said first relays via circuits independent of said 105 signaling circuit.

62. A telephone system comprising talking circuit conductors, automatic connectors, a selector for extending connection to an idle connector having vertical motion to select groups and rotary motion to connect 110 with a line in the selected group, and a source of signaling current and signaling circuits associated with said selector and controlled by relays included in the selector for controlling the transmission of ringing 115 or signaling current to the called subscriber, magnets in said selector for operating the same, said magnets controlled by said relays via circuits excluded from said talking conductors.

63. A telephone system comprising telephone lines, suitable connector switches for extending connection to said telephone lines, automatic progressively movable selector switches for trunking calling telephone lines into connection with idle connector switches, said selectors and connectors having vertical motion to select groups and rotary motion to connect with a line in the selected group, and a battery and circuits in said selectors 125 130

having impedance for supplying talking current through said automatic selectors to the calling and called telephone lines.

64. A telephone system comprising telephone lines, suitable connector switches for extending connection to said telephone lines, having vertical motion to select groups and rotary motion to connect with a line in the selected group, automatic progressively movable selector switches for trunking calling telephone lines into connection with idle connector switches, and a source of current and circuits associated therewith and controlled by relays in said selectors for supplying ringing current through the said trunking selectors to the called telephone lines, magnets for said selectors, said magnets controlled by said associated relays via circuits independent of said signaling circuit.

65. In a telephone system, a trunk-line having three conductors, a progressively movable switch for automatically extending connection to said trunk-line, having vertical motion to select groups and rotary motion to connect with a line in the selected group, a relay controlling the continuity of the connection extended to the trunk-line, a relay having its winding included in the third conductor of said trunk-line, and an energizing circuit for said first-mentioned relay, said energizing circuit controlled by the said relay in the third conductor of the trunk-line.

66. A telephone system comprising a three-conductor trunk-line, an automatic progressively movable switch for extending connection to said trunk-line, having vertical motion to select groups and rotary motion to connect with a line in the selected group, a relay having its winding included in the third conductor of said trunk-line, and a circuit through said automatic switch controlled by said relay.

67. A telephone system comprising telephone lines, a connector for automatically seizing and extending connection to any one of said lines, having vertical motion to select groups and rotary motion to connect with a

line in the selected group, said connector provided with terminals of said lines arranged in a plurality of levels, a magnet for selecting a terminal in any level, a single line relay and a private magnet connected directly to the trunk line, by which the operations of the connector are controlled, and a side switch operated by said private magnet.

68. In a telephone system, an automatic switch provided with a bank of terminals arranged in different levels, and with a magnet for selecting a terminal in any level, having vertical motion to select groups and rotary motion to connect with a line in the selected group, a line leading to said switch, and a private magnet in said switch normally connected with one side of said line.

69. A telephone system comprising a three-conductor trunk-line, an automatic switch to which the said line leads, having vertical motion to select groups and rotary motion to connect with a line in the selected group, an electromagnet in said switch, and an automatic auxiliary electromagnetically controlled switch associated with said switch for shifting said electromagnet from its normal connection with one of the talking conductors of said trunk-line to the third conductor thereof.

70. In a telephone system, an automatic connector switch, a trunk line, a magnet in said connector switch, a battery, means for extending a talking circuit to said connector switch over conductors of said trunk line before the connector is operated, said trunk line having a conductor excluded from the talking circuit, and a relay adapted to remain energized in series with said connector, battery, and magnet during conversation over the conductors of the trunk line.

Signed by me at Chicago, Cook county, Illinois, this 21st day of March, 1907.

EDWARD A. MELLINGER.
